UNITED STATES PATENT OFFICE.

RUSSELL BARR WILLIAMSON, OF WHITEFISH BAY, WISCONSIN, ASSIGNOR TO ANTHONY S. MADALA.

DESIGN FOR A MAIL BOX.

Application filed July 18, 1927. Serial No. 22,792. Term of patent 3½ years.

To all whom it may concern:

Be it known that I, RUSSELL BARR WILLIAMSON, a citizen of the United States, residing in the village of Whitefish Bay, in the county of Milwaukee and State of Wisconsin, have invented a new, original, and ornamental Design for Mail Boxes, of which the following is a specification, reference being had to the accompanying drawings, forming part thereof.

I claim:

The ornamental design for a mail box as shown.

RUSSELL BARR WILLIAMSON.
